UNITED STATES PATENT OFFICE.

JULIAN KENNEDY, OF PITTSBURGH, PENNSYLVANIA.

DRIVING MECHANISM FOR ROLLING-MILLS.

1,112,220.

Specification of Letters Patent. Patented Sept. 29, 1914.

Application filed October 22, 1913. Serial No. 796,607.

To all whom it may concern:

Be it known that I, JULIAN KENNEDY, a citizen of the United States, residing at Pittsburgh, in the county of Allegheny and 5 State of Pennsylvania, have invented a new and useful Improvement in Driving Mechanism for Rolling-Mills, of which the following is a full, clear, and exact description, reference being had to the accompanying 10 drawings, forming part of this specification, in which—

Figure 1 is a view, largely conventional, showing a portion of a rolling mill, partly in elevation, and partly in vertical section. 15 Fig. 2 is a vertical section at one side of the driving mechanism; Fig. 3 is a section through the casing on the line III—III of Fig. 2, the driving gears being shown in elevation. Fig. 4 is a detail view of a portion of the driving shaft and its pinion.

My invention relates to gear-driving mechanism for rolling mills, and is designed to reduce the number of spare parts kept in stock, and to provide a simple and efficient 25 driving mechanism for the rolls which will avoid torsion on the shaft of the driving pinion and allow interchanging of the driving gears one for the other.

Referring to the accompanying drawings, 30 in which I have shown my invention as applied to a three-high mill, the numeral 2 designates the top roll of the mill, 3 the intermediate roll, and 4 the lower roll.

5 and 6 designate the drive shafts for the 35 rolls 2 and 4, respectively. These shafts are journaled in parallel relation, one above another, in an auxiliary housing 7 which is in endwise alinement with, but at a distance from the main housing 8. The two shafts 5 and 6 are connected with the respective rolls 2 and 4 by means of the usual spindles 9 and 10.

Rigidly secured to each of the shafts 5 and 6 is a gear wheel 11. These gears 11 are of 45 relatively large diameter and are placed in adjacent vertical planes in overlapping arrangement. The gears are of the double helical or herringbone type.

12 designates the driving shaft upon 50 which is formed, or to which is secured a pinion portion which engages the teeth of both the gear wheels 11. The pinion portion forms a double pinion, the parts 13 and 14 thereof which mesh with the respective 55 gear wheels 11 being reversed with respect to each other, the teeth on the two gear

wheels 11 being correspondingly reversed with relation to each other. I also preferably provide each of the shafts 5 and 6 with a wabbler or connection portion 15 at each end, so that either shaft may be used reversibly end for end for the purpose now to be described. It will be noted that the two gears 11 are of similar form, but that the reverse arrangement of their teeth is due to the fact that one of the gears is reversed side for side with respect to the other. Therefore, either gear may be used interchangeably with the other by simply turning it around. By also making the shafts 5 and 6 reversible end for end, it will be apparent that a spare gear for each shaft may be carried in stock and can be used either at the top or the bottom, as may be necessary. If the two pinion portions 13 and 14 were 65 not reversed with respect to each other, it would be necessary to carry a spare shaft with a wheel loose thereon and assemble and key them after it was determined in which position they were to be placed. By the 70 construction shown, however, the gear wheel can be placed on a spare shaft, ready for operation, and this shaft and gear can be used either at top or bottom. It will also be observed that by the reversed arrangement of the teeth of the two pinion portions 75 13 and 14 no clearance groove is needed between the adjacent ends of these two portions. This adds considerably to the strength and also enables the two pinions, 80 as well as the two gears 11, to be placed closer together. This is of advantage since it reduces the strain on the driving shaft 85 between the pinions.

What I claim is:

1. A gear-driving mechanism for rolling mills, comprising a gear housing, overlapping toothed wheels secured upon shafts within said housing and adapted for driving connection to the rolls, and a driving shaft 100 having a pinion gear meshing with the toothed wheels within the gear housing, said toothed wheels having inclined teeth reversed in direction, substantially as described.

2. A gear-driving mechanism for rolling mills, comprising a gear housing, overlapping toothed wheels rigidly secured to two shafts mounted in said housing, said wheels being of the herring bone type and with the teeth reversed directly to each other, the 105 shafts being interchangeable and adapted

for connection to the rolls at either end, and a pinion drive for said toothed wheels, substantially as described.

3. A gear-driving mechanism for three-
5 high rolling mills, comprising a gear housing having overlapping toothed wheels se-
cured to shafts mounted therein, said toothed
wheels being of the herring bone type with
the teeth reversed thereon and said shafts
10 being reversible and adapted for connection
to the rolling mill at either end, and a driv-

ing shaft within the housing having a pinion
with two portions reversed in direction and
engaging said toothed wheels, substantially
as described.

15

In testimony whereof, I have hereunto
set my hand.

JULIAN KENNEDY.
